UNITED STATES PATENT OFFICE.

WAYNE M. GRIFFIN, OF MANCHESTER, NEW HAMPSHIRE.

SHOE-UPPER.

No. 877,075.

Specification of Letters Patent.

Patented Jan. 21, 1908.

Application filed September 25, 1907. Serial No. 394,428.

To all whom it may concern:

Be it known that I, WAYNE M. GRIFFIN, a citizen of the United States, residing at Manchester, in the county of Hillsboro, State 5 of New Hampshire, have invented an Improvement in Shoe-Uppers, of which the following description, in connection with the accompanying drawings, is a specification, like letters on the drawings representing like 10 parts.

This invention pertains to uppers for boots and shoes and is designed to provide a substantially seamless upper having the same excellence of shape and fit as those having a 15 plurality of assembled parts.

The invention comprehends an upper for boots and shoes, and the blank from which the upper is formed.

In order that the principles of the invention 20 may be more readily understood, I have disclosed a single type or embodiment in the accompanying drawings, wherein—

Figure 1 is a plan of the blank from which the upper embodying my invention may be 25 formed; Fig. 2 represents the upper after the flies have been positioned; and Fig. 3 represents a side elevation of a shoe embodying my invention.

Referring more specifically to the drawings, the blank from which a shoe upper embodying my invention may be formed is represented at 1 (Figs. 1 and 2). I contemplate forming the body or forward portion of the upper, the flies and the tongue from one 35 integral piece. To that end and in the selected embodiment of my invention, I longitudinally slit the blank 1 along suitable lines 2 and 3 (see Fig. 1) to substantially the points 4 and 5 to provide the tongue 6, the contour 40 of which may be of any desired type. Therefore the path or direction of the lines of cut 2 and 3 depends upon the type of tongue that is desired. By slitting the blank along the lines 2 and 3, I thereby form the inner or 45 securing edges of the flies 7 and 8. In order to provide free lower or forward ends for the said flies 7 and 8, I cut the blank at or adjacent the base of the tongue along a transverse line preferably and generally speaking substantially normal to that of the axis of 50 the tongue.

In the present embodiment of my invention such transverse cut is effected by extending the cuts 2 and 3 from the points 4 and 5 laterally or toward the side edges of the blank to any suitable point, such as indi-

cated at 9 and 10 in Fig. 1, such prolongation of the cuts 2 and 3 being herein indicated as extending in a direction substantially normal to the direction of the cuts 2 and 3 at or 60 adjacent the base of the tongue 6. The cuts extending between the points 4 and 9 and 5 and 10 should to secure the best results be as short as possible consistent with the formation of a sufficient forward or free edge of the 65 flies and should be such as to preserve unimpaired the main or body portion of the flies 7 and 8. Having thus fashioned a blank as indicated in Fig. 1 I preferably, and in the present type of the invention, crimp or stretch 70 the blank at the zones 11, 12 and 13, indicated in Fig. 1, the zones 11 and 13 forming substantially continuations of the horizontal cut previously described as extending between the points 4 and 9 and 5 and 10, and 75 the zone 12 being formed in the forward portion of the upper along the line of the axis of the tongue 6.

By crimping the blank along the zones indicated, the flies 7 and 8 are laterally displaced inwardly or toward each other, so 80 that the forward ends of said flies 7 and 8, which extend respectively between the points 4 and 9 and 5 and 10, are superposed upon or overlie the opposite edge of the said 85 horizontal cut, as indicated at the points 14 and 15 in Fig. 2.

It will be apparent that by the described construction and mode of operation but a very slight and almost negligible raw edge is 90 present upon the inner surface of the shoe. The inwardly displaced flies 7 and 8 are secured in their described position in any suitable manner, as by short lines of stitching 16 and 17, which should terminate at such inner points 18 and 19 as to leave a portion of the forward or lower ends of the flies 7 and 8 unattached to that portion of the upper that they are superposed upon, thereby permitting the ready opening up of the flies and the 100 insertion of the foot of the wearer into the completed shoe.

It will be observed that by the practice of my invention, I am enabled to provide a shoe having but a negligible raw inner edge 105 and one in which the lines of stitching 16 and 17 exist upon such portion of the shoe that no discomfort is given the wearer. Inasmuch as the tongue is integral with the body of the upper, I avoid a seam along the 110 base of the tongue, which in a new shoe occasions discomfort.

It is apparent that while my invention is particularly applicable to the type of shoe known as bluchers, it may also be employed with advantage in other styles of footwear, 5 as for example, oxfords and boots, and that the tongue 6 may be a bellows tongue or of any suitable type. It is moreover apparent that the toe 20 of the boot or shoe may be a separate piece secured in any suitable manner to the upper or may be integral therewith, as will be apparent to those skilled in the art.

Having thus described one type or embodiment of my invention, I desire it to be understood that although specific terms are employed, they are used in a descriptive and generic sense and not for purposes of limitation, the scope of the invention being set forth in the following claims.

20 Claims.

1. A seamless shoe comprising an upper composed of a single piece longitudinally slitted to form the inner or securing edges of the flies and having a tongue formed integral therewith, the upper being cut transversely of its length adjacent the base of the tongue to form lower forward ends only for the said flies, said transverse cut terminating at said lower forward ends of said flies, the said 25 lower ends being positioned to overlie the opposite edge of the transverse cut and secured to the forward or body portion of the upper for a portion only of the extent of the forward ends of such flies, thereby permitting the opening up of the flies.

2. A seamless shoe comprising an upper composed of a single piece longitudinally slitted to form the inner or securing edges of the flies and having a tongue formed integral therewith, the upper being cut transversely of its length adjacent the base of the tongue to form lower forward ends only for said flies, said transverse cut terminating at said lower forward end of said flies, the said upper being crimped upon opposite sides along 30 axial lines forming substantially opposite

continuations of said transverse cut, said lower ends of said flies being positioned to overlie the opposite edge of the transverse cut and secured thereto only at and closely 50 adjacent opposite ends of said transverse cut, thereby leaving the inner portions of the lower ends of said flies unattached to said opposite edges of the transverse cut.

3. A seamless shoe comprising an upper 55 composed of a single piece longitudinally slitted to form the inner or securing edges of the flies and having a tongue formed integral therewith, the upper being cut transversely of its length adjacent the base of the tongue to form lower forward ends only for said flies, said transverse cut terminating at said lower forward end of said flies, the said upper being crimped upon opposite sides 60 along axial lines forming substantially opposite continuations of said transverse cut, and also crimped along a line forming an extension of the tongue, said lower ends of said flies being positioned to overlie the opposite edge of the transverse cut and secured thereto only at and closely adjacent opposite ends of said transverse cut, thereby leaving the inner portions of the lower ends of said flies unattached to said opposite edges of the transverse cut.

4. A blank for a shoe upper composed of a single piece longitudinally slitted to form the inner or securing edges of the flies and having a tongue formed integral therewith, said blank being cut transversely of its length 70 adjacent the base of the tongue to form lower ends for the said flies, said transverse cut terminating at said lower forward ends of said flies.

In testimony whereof, I have signed my 75 name to this specification, in the presence of two subscribing witnesses.
